**SEALING CAP FOR INLET BLOOD
PLUG OF DIALYSIS COIL**

Lester Zimmerman, Hicksville, N.Y., assignor to
Vernitron Medical Products, Inc., Deer Park, N.Y.

Filed Apr. 13, 1973, Ser. No. 351,050

Term of patent 14 years

Int. Cl. D24—01

U.S. Cl. D83—1 F

FIG. 1

FIG. 2

FIG. 3

FIG. 4

FIG. 1 is a perspective view of a sealing cap for inlet blood plug of dialysis coil showing my new design;

FIG. 2 is a top plan view thereof;

FIG. 3 is a front elevational view thereof;

FIG. 4 is a bottom plan view thereof.

I claim:

The ornamental design for a sealing cap for inlet blood plug of dialysis coil, substantially as shown.
